UNITED STATES PATENT OFFICE

2,446,909

KNIFE SHARPENER

Francis W. Davis, Belmont, Mass.

Application August 24, 1945, Serial No. 612,321

6 Claims. (Cl. 76—87)

1

This invention relates to knife sharpeners of that type which employ hardened partly overlapping beveled disks between which the edge of the knife to be sharpened is drawn.

One of the objects of this invention is to provide means by which the disks may be turned readily from time to time to present fresh cutting edges into effective position.

Another object of the invention is to provide a pair of sharpening edges for the knife in which the disks are differently spaced, thus to facilitate a rough sharpening action to one taper, and a finish sharpening action to a different taper, and to facilitate the removal of any edge fin or feather on the knife being sharpened and occasioned by the first or rough sharpening operation.

A further object of the invention is to provide a fixed support with which the sharpener may be quickly engaged or disengaged, so that it may be used either while supported in the hand, or in a rigidly fixed position.

Still another object is to provide a readily detachable guide by which a scissors blade may be supported in sharpening position with respect to one of the sharpening disks.

Further objects and advantages will appear from a complete description of an embodiment of the invention shown in the accompanying drawings in which

Figures 1 and 2 are top edge and front elevations, respectively, of a sharpener constructed in accordance with this invention.

Figure 3 is a detail sectional view to a larger scale on line 3—3 of Figure 2.

Figure 4 is a somewhat diagrammatic view to a larger scale, and showing the knife edge portion in section, of cooperating portions of the left hand and center disk as shown in Figure 2.

Figure 5 is a view similar to Figure 4, but showing the center and right hand disks.

Figure 6 is a detail sectional view on line 6—6 of Figure 5.

Figure 7 is a detail sectional view through the edge portion of a knife blade sharpened as shown in Figure 5.

Figure 8 is a view similar to Figure 4, but showing in full lines a blade in the condition of Figure 7, and in dotted lines the corrective effect of the final finish sharpening by the left hand and center disks.

Figures 9 and 10 are front and top plan views, respectively, of a rigid support for the sharpener.

Figures 11 and 12 are left and right hand elevations, respectively, of the same.

2

Figure 13 is a perspective view of a scissors blade support.

Figure 14 is a view similar to a portion of Figure 9, but showing the support of Figure 13 in operative position.

Figure 15 is a detail sectional view on line 15—15 of Figure 14.

Figure 16 is a somewhat diagrammatic view illustrating the relations between the scissors blade support, a scissors blade in sharpening position, and a sharpening disk.

Figure 17 is a fragmentary perspective view of the parts shown in Figure 16.

Referring to the drawings, at 1 is indicated a support of any suitable description, but herein shown as provided with a handle 2 at one end. The supporting portion of the support 1 is formed as a flat plate, the end opposite to the handle 2 being suitably supported during use against any convenient fixed element such as a table or upright member of any suitable description.

Journalled on the support 1 are three peripherally beveled disks cooperating with each other in two pairs, one pair comprising disks 3 and 4, and the other comprising the disks 4 and 5, the disk 4 being common to the two pairs.

As best shown in Figure 3, each of the disks is journalled on a headed pivot member 6 which passes through the support 1 and may have suitable means for securing it on the back face of the support as by the nut 7 threaded onto its rear end. Each of the disks has bearing against its forward face a knurled knob 10. This knob may be provided with one or more rearwardly directed

projections such as the pins 11 which engage in perforations 12 in the corresponding disk and serve to connect the two together for angular adjustment about the pivot member 6. The head 15 of each pivot member may be set into a recess 16

in the outer end of the knob 10 and beneath the head 15 and in the base of the recess 16 may be positioned a spring shown as a Belleville washer 17. This acts to yieldingly tighten the knob, disk, and support together for frictional turning of

the knob and disk. Thus each disk may be turned by grasping its knurled knob and turning it to present a fresh cutting edge of the disk into active position with respect to the knife to be sharpened.

It will be noted that the spacing between the axes of the center disk 4 and the end disks 3 and 5 is different, as shown the distance between the axes of the disks 3 and 4 being less than

between the axes of the disks 4 and 5. This causes the active portions of the disks 3 and 4

55

to be somewhat higher from the central longitudinal axis of the support 1 which passes through the centers of the pivot members than the active portions of the disks 4 and 5, and the angles at which the cylindrical projections of the disk peripheries intersect is flatter between the disks 3 and 4 than between the disks 4 and 5 as shown by comparison of Figure 4, which shows the portions of the disks 3 and 4, and Figure 5 which shows portions of the disks 4 and 5. If now the support be held against a fixed member and a knife be drawn thereacross with its edge presented between the disks 4 and 5 in the direction shown by the arrow in Figure 6, the larger diameter edges of the beveled disks scrape away portions from opposite sides of the knife blade adjacent to its edge as shown at 20, this tending to reduce the knife edge to the general contour shown in Figure 5, except that the later engagement of the side of the knife edge against the periphery of the disk 4 tends to deflect the extreme edge of the blade laterally as shown in Figure 7.

If now the knife be given a light finishing sharpening movement between the disks 3 and 4, as shown in Figure 8, this feather may be removed or straightened and the extreme point of the edge reduced to a somewhat flatter angle following the contours imparted thereto by reason of the closer spacing of the disks 3 and 4 than of the disks 4 and 5. Thus a final finishing cut of more obtuse angle than the first or roughing cut is produced on the knife edge and any feather occasioned by the preliminary or rough sharpening may be eliminated. The finishing stroke of the knife should be done under light pressure, as otherwise a feather edge might be thrown in the opposite direction by reason of the action of the disk 4 occurring after the action of the edge of the disk 3.

It will also be noted from an inspection of Figure 2 that the support 1 is prolonged downwardly below the apex of the peripheries of the cooperating disks so as to prevent the knife from being drawn between the disks at this side of the support where drawing of the knife in the same direction of the arrow of Figure 6 between the disks would not act to sharpen the knife as the knife edge would be presented first to the back faces of the cutting disk edges. The upper edge of the support 1 is shown as notched at 25 between the disks 4 and 5 so as to permit the knife edge to pass fully into sharpening relation.

In some cases it may be desired to support the sharpener rigidly instead of holding it in the hand. Where this is desired, it may be engaged in a supporting bracket such as is shown in Figures 9 to 12. This bracket comprises a strip 30 having upturned end portions 31 and 32. The intermediate portion 33 of the bracket may be secured to any fixed member such as a wall or table 34 as by screws 35. One upstanding end portion, such as 31, is provided with a closed slot 36 therein of sufficient size to receive therein the free end 37 of the support 1 to which the handle 2 is secured. The other end portion 32 is provided with an open top slot 39 within which the intermediate portion of the support and handle 2 may be thrust so that the handle and support take the position shown in dotted lines in Figures 9 and 10. In order to insure that the sharpener is assembled in the support right side up so that the disks are presented in sharpening position, one side portion 38 at one side of the slot 39 may be bent inwardly as shown best in

Figures 9 and 10. Should it be attempted to insert the sharpener upside down in the bracket, this end 38 would strike against the sharpening disk 3 and prevent the placing of the sharpener in the bracket.

It will be noted that the end portions 31 and 32 are inclined slightly toward each other, this causing these parts to exert a frictional drag on the end disks 3 and 5, the end portions 31 and 32 springing apart slightly when the sharpener is being inserted in the bracket, so that the sharpener is held frictionally, but can be removed when desired by pulling upwardly on the handle 2 and then moving the sharpener lengthwise to disengage its end portion from the slot 36.

The bracket may also be provided with means for supporting a guide for a scissors blade by which this blade may be presented to one of the sharpening disks in sharpening position. Such a guide is shown detached in Figure 13 at 40. As shown it comprises a lower portion slit to form a pair of spring feet 41, the upper portion of the guide being bent out of the plane of the feet 41 to form a guide face 42 against which the scissors blade 44 may be presented. The feet 41 are engaged with the intermediate portion 33 of the bracket and to facilitate this, this intermediate portion may be upwardly bowed at 43, where it is provided with a transverse slot 45. This slot is of sufficient length to permit the feet 41 to be sprung toward each other slightly and then inserted therein and released, whereupon the spring engagement of the feet 41 with the slot ends holds the guide 40 in proper position. The space between the feet 41 also provides room for the overlapping edge portions of the sharpening disks 4 and 5 to extend, as shown in Figure 17. The portion 40 provides a flat support for a scissors blade 44 with its face 46 adjacent to the cutting edge 47 in engagement with the cutting edge of the disk 5. With the blade so supported, it is only necessary to pull it across the cutting edge of the disk as shown by the arrow in Figure 17 to sharpen the blade.

From the foregoing description of an embodiment of this invention, it should be evident to those skilled in the art that various changes and modifications might be made without departing from the spirit or scope of the invention.

I claim:

1. A knife sharpener comprising a support, a pair of peripherally beveled hard sharpening disks, a headed pivot member securing each of said disks to said support in overlapping relation and with beveled peripheries facing in the same direction, a knurled knob also journaled on each pivot member and operatively engaging the adjacent disk, and a spring positioned between each pivot head and the adjacent knob and holding the adjacent disk and knob for frictional turning on said pivot.

2. The combination with a sharpener having a handled support and a plurality of overlapping sharpener disks carried by said handled support, of a bracket for securing in fixed position and provided with arms to frictionally engage the end disks of said sharpener, one of said arms having a closed slot for receiving therein the outer end portion of said handled support and the other of said arms having an open ended slot into which an intermediate portion of said handled support may be pressed when said outer end portion has been inserted into said closed slot.

3. The combination with a sharpener having a handled support and a plurality of overlapping

sharpener disks carried by said handled support, of a bracket for securement in fixed position and provided with arms to frictionally engage the end disks of said sharpener, one of said arms having a closed slot for receiving therein the outer end portion of said handled support and the other of said arms having an open ended slot into which an intermediate portion of said handled support may be pressed when said outer end portion has been inserted into said closed slot, a portion of 10 said other arm at one side of said slot being deflected toward the other of said arms to prevent the engagement of said sharpener in incorrect position in said bracket by interference between said deflected portion and one of said disks.

4. The combination with a sharpener having a handled support and a plurality of overlapping sharpener disks carried by said handled support, of a bracket for securement in fixed position and provided with arms to frictionally engage the end disks of said sharpener, one of said arms having a closed slot for receiving therein the outer end portion of said handled support and the other of said arms having an open ended slot into which an intermediate portion of said handled support may be pressed when said outer end portion has been inserted into said closed slot, and a guide for a scissors blade carried by said support, said guide presenting a face portion against which said blade may be engaged in position to present the cutting edge of said blade in sharpening relation to one of said disks.

5. The combination with a sharpener having a handled support and a plurality of overlapping sharpener disks carried by said handled support, of a bracket for securement in fixed position and provided with arms to frictionally engage the end disks of said sharpener, one of said arms having a closed slot for receiving therein the outer end portion of said handled support and the other of said arms having an open ended slot into which an intermediate portion of said handled support may be pressed when said outer end portion has been inserted into said closed slot, and a guide for a scissors blade carried by said support, said 45

guide presenting a face portion against which said blade may be engaged in position to present the cutting edge of said blade in sharpening relation to one of said disks, said guide and bracket having portions coacting to releasably support said guide in operative position.

6. The combination with a sharpener having a handled support and a plurality of overlapping sharpener disks carried by said handled support, of a bracket for securement in fixed position and provided with arms to frictionally engage the end disks of said sharpener, one of said arms having a closed slot for receiving therein the outer end portion of said handled support and the other of 15 said arms having an open ended slot into which an intermediate portion of said handled support may be pressed when said outer end portion has been inserted into said closed slot, and a guide for a scissors blade, said guide presenting a face portion against which said blade may be engaged in position to present the cutting edge of said blade in sharpening relation to one of said disks, said guide having spaced resilient feet and said bracket having a slot into which said feet may be 20 sprung for releasably securing said guide in operative position on said bracket.
